United States Patent Office.

IMPROVED LUBRICATING OIL CAN AND LAMP.

ELIAS ASHCROFT, OF SOUTH BOSTON, MASSACHUSETTS.

Letters Patent No. 60,117, dated December 4, 1866; antedated November 29, 1866.

SPECIFICATION.

TO ALL WHOM IT MAY CONCERN:

Be it known that I, ELIAS ASHCROFT, of South Boston, in the county of Suffolk, and State of Massachusetts, have invented a new and useful improvement in Oil Cans, which I term a "combined oil can and lamp;" and I do hereby declare that the following is a full, clear, and exact description thereof, which will enable those skilled in the art to make and use the same, reference being had to the accompanying drawings, forming part of this specification, in which—

Figure 1 is a vertical central section of my combined oil can and lamp.

Figure 2 is a top view of the same.

Similar letters of reference indicate corresponding parts.

This invention consists in constructing an oil can with two spouts or nozzles, the one for pouring out the oil, and the other for the insertion of a wick which can be lighted for the purpose of showing clearly where the oil is to be poured, the flame being near the end of the oil spout, as will be hereafter explained. To enable others to understand my invention I will now proceed to describe it.

A represents the body of an oil can, which may be of the ordinary or any other suitable construction. Inside of this can, a short distance above the bottom thereof, I place a perforated plate or disk, B. Above this plate, B, a tube, C, is secured to the side of the can, and opening therein, and which extends upward; and below the plate, B, another tube, D, is secured, which also extends upward. The former, C, is intended for the wick-tube, and into it is inserted the wick, which runs down into the can and lies upon the plate, B, as shown in red in fig. 1. The latter, D, is the oil-spout, and inasmuch as it opens into the can below the plate, B, its mouth cannot be clogged by the wick.

This arrangement produces a light which follows or goes with the spout of the oil can and enables the person to see just where to deposit the oil; and the device is at once convenient and useful.

What I claim as new, and desire to secure by Letters Patent, is—

The combination of the tube D, tube C, plate B, and can A, constructed and arranged in the manner and for the purpose herein specified.

ELIAS ASHCROFT.
